UNITED STATES PATENT OFFICE.

CHARLES H. MILLER, OF WEST PITTSBURG, PENNSYLVANIA, ASSIGNEE TO SAFETY-
ARMORITE CONDUIT COMPANY, OF PITTSBURG, PENNSYLVANIA, A CORPORATION
OF PENNSYLVANIA.

FLEXIBLE CONDUIT.

942,787.

Specification of Letters Patent.

Patented Dec. 7, 1909.

Application filed July 25, 1907. Serial No. 385,517.

To all whom it may concern:

Be it known that I, CHARLES H. MILLER, a citizen of the United States, of West Pittsburg, in the county of Lawrence, Pennsylvania, have invented a new and useful Flexible Conduit, of which the following is a full, clear, and exact description, reference being had to the accompanying drawings, forming part of this specification, in which—

10 Figure 1 is an elevation partly in section of my improved conduit; and Fig. 2 is a cross section of the same. Fig. 3 is a view similar to Fig. 2 but showing a modification.

My invention relates to a class of flexible conduits for electric wires or electrical conductors, and the object of the invention is to provide a simple, strong and durable insulating conduit, which may be easily bent or flexed, and yet is stiff to a desirable degree.

20 In the preferred form of my invention the conduit is provided with an interior lining 2, which is preferably formed of oilcloth. This oilcloth is fed in a strip to the forming mandrel, and there butted or 25 lapped at the longitudinal seam. It not only gives a smooth inner surface to the conduit, but also forms a waterproof lining. This inner lining may also be formed of a wax or composition applied to the mandrel, 30 and then covered with, say, a cloth such as muslin, and then coated with another layer of composition. Where oilcloth or a composition lining is used, I preferably spread or sprinkle soapstone or a smooth powder or 35 material over its inner surface to prevent any clinging tendency. Over this lining of oilcloth or composition, which forms a smooth raceway of preferably waterproof material, a tubular fabric 3 is braided or 40 woven in the ordinary manner, this preferably being of cotton. This material is then saturated with a solution which is preferably of a fireproof nature, and over the braided tube 1 then preferably helically 45 wind a strip of paper 4, which covers and surrounds the waterproof braiding. The cotton or material for braiding or weaving the tubular fabric may be treated to fire- 50 proof it before it is formed into the tube and the winding may be formed of wooden or other strips instead of paper strips. The tube may then be covered with another woven or braided tube 5, and the tube is then preferably treated with another layer of

waterproofing compound, and may or may 55 not be sprinkled with mica flakes or other non-inflammable material to render it more fireproof.

The advantages of my invention result from the smooth raceway and lining afforded by the inner smooth composition, which is preferably waterproof; and also from the peculiar stiff and yet flexible nature of the finished conduit.

The oilcloth center, if oilcloth is used, may 60 be pasted along the overlapping seam or may be simply butted at the longitudinal seam and adhere to the inner surface of the braiding by reason of the saturating solution. The lining may also be split into two 65 layers, the inner of which may be a smooth coating of composition 6 and the next a fabric 7; and in this type the cotton woven covering over the oilcloth can be dispensed with and a muslin covering 8 of fabric em- 70 ployed. In this case the tube would consist of an inner lining of smooth composition 6, then a fabric 7, then another fabric 8, then a coating of waterproofing solution 9, then helically wound paper strips 10, and 75 then a woven or braided tubular fabric 11. The whole would then be saturated with a waterproofing solution and the mica layer may or may not be sprinkled on as desired.

Other variations can be made in the conduit without departing from my invention.

I claim:

1. A non-metallic flexible conduit for electric wires, having an inner layer provided with a smooth interior face, and a tubular 90 braided or woven fabric surrounding said inner layer and saturated with a protecting substance; substantially as described.

2. A non-metallic flexible conduit for electric wires, having an inner layer provided 95 on its inner surface with a coating or lining of smooth material, a tubular braided or woven fabric surrounding the inner layer and saturated with a fireproofing solution, and a helically wound strip of paper sur- 100 rounding and covering the fabric; substantially as described.

3. A flexible non-metallic conduit for electric wires, comprising an inner layer of oil cloth, a tubular braided or woven fabric 105 surrounding the oil cloth, a flexible strip wound helically over said fabric, another woven or braided tubular fabric surround-

ing the helically wound strip, and an outer layer of protecting compound; substantially as described.

4. A flexible non-metallic conduit for electric wires, comprising an inner fabric tube having a smooth interior surface, a second fabric tube surrounding the first and coated with a waterproofing solution, a helically wound paper strip surrounding the fabric tube, a woven or braided tubular fabric sur-

rounding the paper strips and saturated with a protecting solution, and an outer covering of mica flakes; substantially as described.

In testimony whereof, I have hereunto set my hand.

CHARLES H. MILLER.
